Primary Examiner — Terry A Wallace**(57) CLAIM**

The ornamental design for a lunch box, as shown and described.

DESCRIPTION

FIG. 1 is an exploded perspective view of a lunch box showing my new design.

FIG. 2 is a perspective view thereof shown in an open position.

FIG. 3 is a front perspective view thereof in a closed position.

FIG. 4 is a front view of FIG. 3.

FIG. 5 is a rear view of FIG. 3.

FIG. 6 is a left side view of FIG. 3.

FIG. 7 is a right side view of FIG. 3.

FIG. 8 is a top plan view of FIG. 3; and,

FIG. 9 is a bottom plan view of FIG. 3.

The broken lines in the drawings illustrate the portions of the lunch box, which form no part of the claimed design.
